Application May 16, 1941, Serial No. 393,790

17 Claims. (Cl. 105—315)

The present invention relates to a rail car having a plurality of duplex bedrooms equipped with facilities for day and night use, the upper and lower rooms providing equally comfortable accommodations.

Among the principal objects of the present invention are the following: To arrange rooms in railway cars at different levels having complete equipment for day and night use and ample spaces for storage of baggage and equipment readily accessible from the upper and the lower rooms and to provide interior furnishings and equipment which are particularly adapted for use in such a car.

Further and other objects and advantages will become apparent as the disclosure proceeds and the description is read in conjunction with the accompanying drawings, in which—

Fig. 1 is a floor plan view of one form of the invention, showing the car from approximately its center to the non-articulated end;

Fig. 2 is a floor plan view of the remainder of the car completing the showing of Fig. 1;

Fig. 3 is a diagrammatic side elevational view showing the general arrangement of the rooms in the car;

Fig. 4 is a perspective view of a portion of the car showing four duplex rooms including the adjoining upper rooms and two lower rooms, one placed on each side of the two upper rooms, the car walls and portions of the partitions being broken away to show the interior arrangement and furnishings;

Fig. 5 is a longitudinal sectional view through a portion of the car showing the interior arrangement of two adjoining lower rooms with an upper room on each side of the lower rooms, the view being taken from inside the rooms looking toward the windows;

Fig. 6 is a vertical longitudinal sectional view showing two adjoining upper rooms with a lower room on each side, and looking from within the rooms toward the outside doors;

Fig. 7 is a horizontal sectional view of the lower rooms taken along the line 1—1 of Fig. 5;

Fig. 8 is a horizontal sectional view through the upper rooms taken along the line 8—8 of Fig. 6;

Fig. 9 is a vertical transverse sectional view taken on the line 9—9 of Fig. 5 through the upper room and step-well looking toward the partition dividing the adjoining upper rooms;

Fig. 10 is a vertical transverse sectional view taken along the line 10—10 of Fig. 5 through the upper room looking toward the sofa;

Fig. 11 is an enlarged detail view of the sofa used in the lower rooms showing the relative positions and the supporting mechanisms for the seat and back portions of the sofa when they are made up for night use;

Fig. 12 is an enlarged detail view similar to Fig. 11 but showing the relative positions and supporting mechanisms when the sofa is made up for day use;

10 Fig. 13 is a fragmentary vertical sectional view taken longitudinally of a sofa seat at the front along line 13—13 of Fig. 5, showing the supporting means at the front of the seat;

15 Fig. 14 is a fragmentary vertical longitudinal sectional view taken at one end of the sofa seat showing the support under the longitudinal center of the seat;

19 Fig. 15 is an enlarged sectional view taken on the line 15—15 of Fig. 12, showing details of the sofa back stop;

20 Fig. 16 is a partial transverse sectional view through a car showing a modified arrangement of the upper room wherein the door leading from the aisle is disposed in the plane of the aisle partition; and

25 Fig. 17 is a vertical view taken longitudinally of the car and through an upper and lower room looking toward the aisle door, the view showing a modified arrangement of the partition separating the upper and lower rooms.

30 Specific embodiments of the present invention are selected for the purpose of disclosure in compliance with Section 4888 of the Revised Statutes. Obviously, many modifications may be made without departing from the scope of the present invention.

35 This application is a continuation in part of applicants' copending application Ser. No. 223,964, filed August 9, 1938.

GENERAL ORGANIZATION

Referring to Figs. 1 to 3 inclusive, the present invention is illustrated by a car 40, mounted on a pair of trucks 41, 42, and having an under-frame, generally indicated at 43, a pair of side frames, indicated at 44, 45, end frames 46 and 47, and a roof 48. The car 40 (as shown) is non-articulated at one end and articulated at its other end. Obviously the invention is not limited to such a car but is equally applicable to one fully articulated or one completely non-articulated.

40 In the region between the trucks 40, 41, the floor is depressed, as indicated at 49 in Fig. 3, to give added head room in the duplex rooms,

and over the trucks a different arrangement of rooms is shown. An aisle 50 extends the full length of the car along one side, and the bedrooms are positioned entirely along the opposite side.

In the embodiment of the invention shown in Fig. 1, the car has a vestibule 51 at the non-articulated end, having the usual vestibule doors 52, 53, and trap doors 54, 55, finishing off the vestibule floor. A door 56 swings inwardly and gives access to the car interior, and a passageway 57 provides access to an adjoining car. At the articulated end a passageway 58 gives access to an adjoining car, and a door 59 is hinged to the car end and closes off this passageway.

A lavatory 60 is positioned at the non-articulated end and is equipped with the usual hopper 61, wash basin 62 and dressing table 63, and a door 64 gives access to the lavatory from the aisle 50. A porter's seat 65 is located at the end of the aisle 50 and is so positioned that the porter has a clear view throughout the entire length of the aisle. A supply and porter's locker 66, and an electric panel locker 67, are positioned at the articulated end of the car, and suitable doors 68, 69, give access to these two lockers, respectively.

Throughout the central or depressed portion of the car body the bedrooms are arranged at two different levels, and are indicated at 70 to 88 inclusive in Fig. 3, while over the non-articulated truck 41 of a pair of rooms 84 and 85, positioned at one level, are arranged en suite. Duplex rooms 71 to 80 inclusive are arranged in pairs, that is, 71, 72, on the lower level, and 73, 74, on the higher level, and so on. Partitions 86 separate adjoining lower rooms, and partitions 87 separate adjoining upper rooms. Similarly, adjoining bedrooms 84 and 85 are separated by partition 88, and between separate single rooms 85 and 70, and 81 and 82, partitions 89 are furnished.

Partitions 84 separate adjoining upper and lower rooms, and extend from the upper room ceiling to the lower room floor, as indicated in Fig. 3.

A modified form of a car end arrangement is shown in Fig. 10, and may be termed a dummy end since there is no vestibule or vestibule doors. The lavatory in this form is situated at the extreme end of the car, and between it and the adjoining bedrooms 84 and 85 is a single bedroom 86. In this form a single bedroom and a pair of rooms en suite are positioned on the same level above the trucks.

Referring again to Figs. 1 and 2, the aisle 50 is bounded on its sides by car side 44 and an aisle partition 91, and at opposite ends of the car partitions 93, 93, close off the ends of rooms 84 and 83, respectively.

CAR FRAMING IN GENERAL

The framing of the duplex car forming the subject-matter of the present invention is covered in detail in the application of Peter Parke and Nils A. Thunstrom, Serial No. 223,963, filed August 9, 1938, for improvements in Railway cars, and said application is hereby incorporated into and made a part of the present application.

As shown in Fig. 9, the underframe includes a center sill 100, extending the full length of the car body, a pair of side sills 101, 102, and longitudinal floor stringers 103 to 108 inclusive. In the present embodiment the center sill 100 is designed to carry the major portion of the buff

and draft loads, and consequently is a straight member throughout its entire length and is so positioned that its longitudinal axis, as defined in the afore-mentioned co-pending application, lies along the line of buff and draft.

Referring to Figs. 1, 2, and 9, the car sides 44, 45, include a pair of corner posts 109, 110, at each end of the car body, respectively, and a plurality of side posts 111 extend from their respective side sills 101, 102, to their respective side plates 111 and 112. Various other vertical and horizontal members are included in the side framing, and the side sheathing is welded or riveted to these members to complete the car framing.

At the articulated end an end sill 113 supports an end frame which includes the corner posts 109, a pair of door posts 114, 115, and a pair of intermediate posts 116, 117. At the non-articulated end a buffer wing, generally indicated at 118, is provided, and includes a vestibule end sill 119, supporting a pair of vestibule end posts 120, 121, a pair of door posts 122, 123, and intermediate posts 124, 125. The roof 48 extends over the entire car body, and the side frames and end frames are suitably tied into the roof. On the aisle side of the car a plurality of window openings 127 are spaced at a single level above the rails, and on the opposite or room side of the car a plurality of lower room windows 128 are positioned along the lower level, and additional upper room windows 129 are provided at a higher level above the trucks.

A pair of skirts 130, 131, extend downwardly from opposite sides of the car and are reinforced by stiffening angles 132 and by skirt-supporting members 133 tying into the car underframe.

ROOM INTERIOR ARRANGEMENT

For the purpose of simplifying the description of the duplex rooms themselves, a group of rooms consisting of two uppers with a lower on each side, as shown in Fig. 4, has been selected. Any particular group in the center portion of the car may be selected, but in the present instance rooms 72, 73, 74 and 75 are chosen (see Fig. 3).

As shown in Fig. 4, each room, whether it be an upper or a lower, is provided with a sofa 140, a hopper 141, a washstand 142, and a medicine cabinet 143. On each side of the partition 86 a table 144 is mounted, one for each of the adjoining lower rooms, and above each is positioned a mirror 145. Similarly on each side of the upper room partition 87 a table and mirror are mounted, the tables in both instances being pivoted to the partitions so that they may be swung out of the way when not in use.

Leading from the aisle 50 to the upper rooms are stairs 146 giving access to both rooms. Outside doors 147, 148, are positioned at the top of the stairs, one on each side of a door post 149, and on each side of the stairs rails 150 are secured to the aisle partition 91. Outer doors 150 close off the lower rooms from the aisle, and on the inside face of each of these doors a full length mirror 154 is mounted as shown in Fig. 6. The windows 128, 129, are positioned so as to give maximum vision to the persons while seated on the sofas 140 of the upper and lower rooms, respectively, and shades 151 roll down from the tops of the windows.

Each upper room utilizes in part the head room of its adjoining lower room, their dividing

partition 84 extending horizontally over the sofa 140 of the lower room, as indicated at 152, and the sofa 140 of the upper room is supported on this horizontal portion of the partition.

As shown in Figs. 5, 6 and 9, below the floor 165 of the two adjoining upper rooms, and behind the stairs 146, is a well divided in the middle by a partition 166 extending from the upper room floor to the floor of the car, and from the car side wall 45 at the bedroom side of the car to the back of the stairs 146. This partition is secured in place by angle bars 167, or other suitable means, and serves as the dividing wall between two storage spaces 168 and 169.

Panels 170, best shown in Figs. 5, 6 and 9, serve as the floor for these storage spaces. The backs 171 of the sofas 140 in the lower rooms are adapted to cover the open sides of the storage spaces, as best shown in Figs. 5 and 6.

As shown in Figs. 6, 7 and 9, resting on panel 170 in each of the spaces 168, 169, is a separate compartment 172, which extends from the second riser 173 of the stairs backwardly into the storage space. Compartment 172 opens in the riser 173, and a door 175 is hinged to the riser (see Fig. 4). Tables indicated at 176 in Fig. 6, may be stored in these compartments, and are supported on strips 177 extending inwardly from the opposite vertical sides of the compartment.

Extending across each of the storage compartments 168, 169, about two-thirds of the way back of the stairs toward the bedroom side wall of the car, is a panel 178, which stretches from the storage space floor 170 to the upper room floor (Figs. 7 and 9), and a second panel 179 extends across each of the storage spaces 168, 169, from the floor 170 to the car floor and is secured in place by means of angle clips 180, or the like, along its lower edge and to the storage space floor 170 along its upper edge, as indicated at 181. These panels 178, 179, serve as one wall of a hopper chute enclosure 138, as best shown in Fig. 9, and a partition 182, shown in Fig. 7, together with a panel 183 and a vertical partition 166, forms the other vertical walls of the hopper chute enclosure. The floor 165 of the upper room has a removable panel portion 164 underneath the hopper which permits access into the hopper chute enclosure.

Since all of the lower rooms are identical in their general arrangement, room 72 (shown in Figs. 4 through 7 inclusive) has been selected for the purpose of description. The sofa 140 is positioned transversely of the car and is spaced slightly from the storage space 168 so as to provide a mattress pocket 196, having panels 197, 198, as its front and back walls, respectively, and a pair of end panels 199, 200, as its side walls. A mattress pocket floor 201 is secured to the walls by angle bars 202 positioned slightly above the car floor. The mattress 203 is housed in this pocket during the daytime when the sofa is being employed for day use, and a rope 204 (shown in Fig. 6) stretches lengthwise across the storage space opening and supports the mattress in an upright position in the pocket. On the side of the hopper chute forming one boundary of the mattress pocket 196 insulation 162 is placed to protect the mattress from excessive heat.

As shown in Fig. 6, above the ceiling of each lower room over the door 150 is another storage space 207, 208 (Fig. 8), and a front panel 209. Transverse panels 210 and 211 divide this space into three compartments 212, 213 and 214, and doors 215, 216, provide access into the compart-

ments 212 and 213, respectively, and are accessible from the adjoining upper bedroom.

Shoe box 236 (see Figs. 6 and 7) is placed under the sofa 140 of the lower room, and a door 217 gives access into the box from the interior of the room and a second door 218 permits access from the car aisle. In the upper room a shoe box 219 is provided, as best shown in Figs. 6 and 8, and doors 220 and 221 permit access into the box from the room and the aisle, respectively.

As shown in Fig. 7, the partition 86 separating the adjoining lower rooms comprises a stationary portion 222, a sliding portion 223, and a hinged door 235. When it is desired to place the two rooms en suite the door 235 may be swung back into one of the rooms, as, for example, room 74, against the outside door 150. If it is desired to further open up the partition between these two rooms, sliding portion 223 may be pushed back into the stationary portion 222. The tables 144 must be in their lowered position before the sliding partition 223 is pushed back, and the spaced walls of the stationary portion 222 of the partition are so arranged that they house the folding tables as well as the sliding partition 223.

Partition 223 is supported on a track 229 by rollers 231, and the free outer end of the partition is provided with a door jamb 238 (shown in Fig. 7) against which the swinging door 224 closes. In the upper rooms partition 87 is entirely stationary except for a hinged door 230. A baggage rack 234 is positioned above the medicine cabinet in the lower room.

SPECIFIC DETAILS

Lower room sofa

In each of the lower rooms the sofa 140 is made up of a seat portion 270, having the back 171, and for day use, as shown in Figs. 6 and 11, the seat 270 inclines upwardly from back to front and the back 171 inclines forwardly from top to bottom. Referring to Figs. 5, 6, 11 to 15, inclusive, it is seen that the seat back 171 is supported at the top by a pair of pins 271 extending outwardly from opposite ends of the back, which ride in slots 272. The seat back is against a pair of stops, generally indicated at 273, positioned one at each side of the back.

As shown in Fig. 15, each of these stops comprises a movable stop member 274, pivotally mounted at 275 in a housing 276. The closed position of the stop is shown in solid lines, and when it is desired to place the stop in use the stop 274 is pivoted outwardly to the position shown in dotted lines. A rod 269 is pivoted to the stop at 277, and rides in a lug 278 which extends outwardly from the housing 276. A coiled spring 279 is mounted on the rod 269 between a spring seat 280 at the pivoted end of the rod and the lug 278. As the movable member 274 is being opened the pivot joint 277 rotates about the stop pivot 275, and during the first part of the rotation the spring 279 is compressed, tending to restore the stop 274 into closed position. As the rotation continues the pivot point 277 moves past dead center, and from there on the spring 279 urges the movable member 274 into open position. The outer face 281 of the member 274 strikes the housing 276 at 282, thereby holding the stop 274 at approximately right angles to the housing 276 when the stop is opened.

As shown in Fig. 11 the sofa seat 270 is in position for day use, and is supported at the front

by a pair of pins 283, one on each side of the seat, and each pin rides in a slot 284 in a support member 285 secured to the room walls by means of angles 286. At the back of the seat 270 a bracket, generally indicated at 287, is secured to the panel 197. This bracket is made up of an angle bar 288 and a second member 289 having two stops 290 and 290. At the center of the seat 270 a pair of rollers 291 project from the side wall and aisle partition of the car, and a guide follower 292 extends from each side of the seat 270 on its under face and rides on the roller 291. This follower is provided with a substantially horizontal face 293 and a concave face 294, and with the seat in the position shown in Fig. 11 the follower is riding on its horizontal face 293.

When it is desired to transform the sofa into a bed for night use, the sofa back 171 is pulled forward a slight amount and stops 273 are pivoted into the housing 276 and then the seat back is swung back into the position shown in Fig. 11. Seat 270 is then raised at its forward end and pulled slightly forward to permit the pins 283 to ride to the top of the slot 284, and then the front portion of the seat is lowered and pushed backwardly until the pins 283 are seated in the lower portion of the slot 284, as shown in Fig. 11. During this process the followers 292 have passed over the rollers 291 until the two assume the relative position shown in Fig. 11. This operation causes the back of the seat to move from the first step 290, as shown in Fig. 12, to the second step 290, as shown in Fig. 11. A metal facing plate 295 is provided at the back of the seat and serves as a bearing surface.

The mattress 203 is housed in the mattress pocket 198 during the daytime, and when it is desired to prepare the sofa for night use the back 171 is swung forwardly and upwardly to the position shown in broken lines in Fig. 6, and a pair of straps 296, one at each end of the sofa back, are secured to hooks 297 which are mounted on the walls of the room. With the sofa back in this position the mattress can be removed from the mattress pocket 198 and the bedding removed from the storage space 188. The seat back is then unhooked and lowered to its night time position and the mattress is placed on the seat 270, as shown in Fig. 11. A pair of angles or other suitable stop means 288 serve as stops for the seat back 171 when the sofa is converted into a bed. Arm rests 268 (Fig. 4) are pivotally secured to the seat backs 171 and are made to swing outwardly for day use.

Upper room sofa

As shown in Figs. 4, 5, 6 and 7, the upper room sofas comprise the seat portion 270 and back 171, but in these rooms the mattress 203 is housed at all times in the sofa back. The relative positions of the seat and back for day use are, as shown in Fig. 6, in room 24, and to convert the sofa into a bed the back is pivoted forwardly and downwardly about points 284 until it assumes the position shown in room 73 of Fig. 6. Retaining walls 265 keep the mattress in place, and a rubber strip 266 extends across the front edge of the retaining wall. Latches 267 hold the sofa back in its raised position for day use.

The interior arrangement described in the selected embodiment of the invention provides maximum economy in space and accessibility to various accommodations. There is practical-

ly no space which is not used, and the locations of the various storage compartments are such that they give the greatest amount of utility.

As shown, the baggage space, located under the upper room floor 165 and behind the stairs 146, has a floor 170 which is positioned above the car floor, and with this particular arrangement there is a small space between the two floors which might be considered as wasted. Should it be found, however, that more storage room is needed, the floor 170 could be eliminated and the entire space used for storage of baggage or equipment, or a removable panel (not shown) may be placed in the floor 170 to provide access to the additional compartment not used at the present time.

Referring to Fig. 4, the doors 147 and 148 leading into the upper room are disposed inwardly from the aisle partition 91, the partition itself at the stairway being turned toward the rooms to form solid walls on both sides of the stairway. In this form, these last mentioned walls and the doors 147 and 148 utilize some of the floor area of the upper rooms.

Referring to Fig. 16, the door 148 for one of the upper rooms is shown in its closed position disposed in the plane of the aisle partition. In this manner, the wall 81, separating the adjoining upper rooms, is extended to the aisle partition, this extended portion being shown at 81' in Fig. 16. Adjacent to the bottom of the door is a box, generally indicated at 410, comprising a vertical side 411 which, as shown, is the lower part of the door 148', a horizontal side 412, which extends inwardly from the door and is disposed immediately above the upper room floor level, and an inclined side 413 extending from the horizontal side 412 to the door 148. These various sides form a triangularly shaped box, and in the diagonal side 413 and the vertical side 411 are grills 414 and 415 respectively, through which air passes from the upper room to the aisle for purposes of recirculation. This triangularly shaped box, if desired, may be used as a shoebox, and a door 416 in the inclined side 413 may provide access into the box from the room, and a second door 417 will provide access into the box from the aisle side. In this manner, the room occupant may place his shoes in this box at night before retiring, and a porter may reach the shoes from the aisle to shine them, as is his usual custom.

The triangularly shaped box at the bottom of the door 148 closes the space between the upper room floor and the aisle door over the stairs. The inclination of the side 413 eliminates the tendency for the room occupant to trip over the closure member, which necessarily is disposed slightly above the upper room floor level in order that the door may be opened inwardly into the room. The door swings inwardly into the room against the upper room sofa, and the shoe-box 410 will be disposed in the space below the seat when the door is opened.

As shown in Fig. 5, the partition 94 separating the upper and lower room is made up of two horizontally spaced vertical portions connected by a horizontal portion 152. This horizontal portion 152 is directly above the lower room sofa, so that a person occupying the lower room sofa in the daytime is sitting directly below this horizontal partition portion.

As shown in Fig. 17, the upper vertical portion 75 of the partition 94 may be generally inclined,

as indicated at 418, so that the horizontal portion 152' is considerably shortened. In this manner, the occupant of the sofa below actually is disposed below the inclined portion 418 of the dividing partition rather than the horizontal portion 152'. Thus, the effect of the overhang of the upper room is not so noticeable to the occupant sitting in the lower room seat. The normal field of vision of such an occupant is such that he is not made aware of the partition above him when he is sitting in the normal position on the sofa.

We claim:

1. In a vehicle, a lower room, an upper room adjacent to the lower room and having its floor above the level of the lower room floor and entirely outside the vertical projection of the lower room, a convertible sofa-bed in the upper room placed within the vertical projection of the lower room and utilizing a portion only of the head room of the lower room, a convertible sofa-bed in the lower room under the sofa of the upper room and closely adjacent to the floor of the upper room, a closed storage space for the lower room underneath the floor of the upper room and behind the sofa-bed of the lower room, a storage space for the upper room directly above the lower room floor and adjacent to the upper room, and means providing access into the lower and upper room storage spaces from the lower and upper rooms respectively.

2. In a vehicle, an upper room extending crosswise of the vehicle, a lower room adjacent to the upper room and also extending crosswise to the vehicle, the upper room having its floor above the level of the lower room floor and entirely outside the vertical projection of the lower room, a sofa in the lower room extending crosswise to the vehicle closely adjacent to the floor of the upper room, a sofa in the upper room directly over the lower sofa, the upper room projecting partially into the head-room area of the lower room, a closed storage space directly above the floor of the lower room, and behind the sofa in the upper room, and means providing access into the storage space from the upper room.

3. In a closed vehicle, an upper room, a lower room below the level of and adjacent to the upper room, the floor of the upper room being entirely outside the vertical projection of the lower room, a common stationary wall separating the two rooms, the wall comprising a vertical portion extending upwardly from the floor of the lower room to a position substantially midway between the floor and roof of the vehicle, a horizontal portion extending into the lower room, and a second vertical portion connecting the end of the horizontal portion to the vehicle roof, a stationary convertible sofa-bed in the lower room under the horizontal portion of the said wall, a convertible sofa-bed in the upper room mounted over the horizontal portion of the wall, each of the sofa-beds being disposed beyond an area of passenger standing space in its respective room, both when the sofa-bed is made up for day use and when it is converted into a bed, storage space beneath the floor of the upper room, a ceiling for each room, the ceiling for the lower room being below the level of the ceiling for the upper room, a storage space above the ceiling for the lower room, and means providing access into said storage space from the upper room.

4. In a vehicle, an upper room, a lower room adjoining the upper room, separate ceilings for said rooms, the ceiling of the lower room being

below the level of the upper room ceiling, a sofa in the upper room below the level of the lower room ceiling, a storage space over the ceiling of the lower room, a vertical wall connecting said ceilings behind said sofa, and means in said wall providing access into the storage space from the upper room.

5. In a vehicle having a lower floor, a pair of oppositely disposed adjacent upper rooms, a ceiling therefor, a partition separating said rooms and constituting an end wall of each, an opposite end wall for each upper room comprising two horizontally offset vertical partition portions extending from said ceiling to the lower floor and connected by a substantially horizontal portion, a sofa for each upper room mounted over the horizontal portion of the offset partition, a floor for the upper rooms extending between the lower vertical portions of the offset partitions, a stairway extending from the lower floor to the floor for the upper rooms, a pair of lower rooms each having a ceiling extending from the upper vertical portion of an offset partition, an end wall extending from said lower room ceiling to the lower floor, a convertible sofa-bed beneath the sofa of the upper room in the angle formed by the lower vertical portion and the lower floor, and a storage space for each upper room above the ceiling of the adjacent lower room.

6. In a vehicle having a lower floor, a pair of oppositely disposed adjacent upper rooms, a ceiling therefor, a partition separating said rooms and constituting an end wall of each, an opposite end wall for each upper room comprising two horizontally offset vertical partition portions extending from said ceiling to the lower floor and connected by a substantially horizontal portion, a sofa for each upper room mounted over the horizontal portion of the offset partition, a floor for the upper rooms extending between the lower vertical portions of the offset partitions, a stairway extending from the lower floor to the floor for the upper rooms, a pair of lower rooms each having a ceiling extending from the upper vertical portion of an offset partition, an end wall extending from said lower room ceiling to the lower floor, a convertible sofa-bed beneath the sofa of the upper room in the angle formed by the lower vertical portion and the lower floor, and a storage space for each lower room beneath the floor of the adjacent upper room and having a floor at substantially the level of the lower floor of the vehicle.

7. In a vehicle having a lower floor, a pair of oppositely disposed adjacent upper rooms, a ceiling therefor, a partition separating said rooms and constituting an end wall of each, an opposite end wall for each upper room comprising two horizontally offset vertical partition portions extending from said ceiling to the lower floor and connected by a substantially horizontal portion, a sofa for each upper room mounted over the horizontal portion of the offset partition, a floor for the upper rooms extending between the lower vertical portions of the offset partitions, a stairway extending from the lower floor to the floor for the upper rooms, a pair of lower rooms each having a ceiling extending from the upper vertical portion of an offset partition, an end wall extending from said lower room ceiling to the lower floor, a convertible sofa-bed beneath the sofa of the upper room in the angle formed by the lower vertical portion and the lower floor having its outer edge spaced from said lower room end wall to provide an area of passenger standing space

on the lower floor directly beneath the lower room ceiling, and a storage space for each upper room above the ceiling of the adjacent lower room.

8. In a vehicle having a lower floor, a pair of oppositely disposed adjacent upper rooms, a ceiling therefor, a partition separating said rooms and constituting an end wall of each, an opposite end wall for each upper room comprising two horizontally offset vertical partition portions extending from said ceiling to the lower floor and connected by a substantially horizontal portion, a sofa for each upper room mounted over the horizontal portion of the offset partition, a floor for the upper rooms extending between the lower vertical portions of the offset partitions, a stairway extending from the lower floor to the floor for the upper rooms, a pair of lower rooms each having a ceiling extending from the upper vertical portion of an offset partition, an end wall extending from said lower room ceiling to the lower floor, a convertible sofa-bed beneath the sofa of the upper room in the angle formed by the lower vertical portion and the lower floor having its outer edge spaced from said lower room end wall to provide an area of passenger standing space on the lower floor directly beneath the lower room ceiling, and a storage space for each lower room beneath the floor of the adjacent upper room and having a floor at substantially the level of the lower floor of the vehicle.

9. In a vehicle, a pair of upper rooms arranged side by side, a lower room on each side of the pair of upper rooms, the floors for the lower rooms being spaced apart, the floors for the upper rooms being disposed above the space between the lower room floors, a stairway in said space extending from the lower room floor level to the upper room floors, a sofa in each lower room having its back adjacent to said stairway, a sofa in each upper room directly above the lower room sofa, an outer end wall for each lower room spaced outwardly beyond the back of the upper room sofa and the front of the lower room sofa to provide passenger standing space on the lower room floor behind the upper room sofa and open to above the level thereof, a vertical wall extending upwardly from the lower room floor behind the lower room sofa, and a storage space for each lower room beneath the floor of the adjacent upper room and behind the said vertical wall, said wall having an opening providing access into said storage space.

10. In a vehicle, a pair of upper rooms arranged side by side, a lower room on each side of the pair of upper rooms, the floors for the lower rooms being spaced apart, the floors for the upper rooms being disposed above the space between the lower room floors, a stairway in said space extending from the lower room floor level to the upper room floors, a sofa in each lower room having its back adjacent to said stairway, a sofa in each upper room directly above the lower room sofa, an outer end wall for each lower room spaced outwardly beyond the back of the upper room sofa and the front of the lower room sofa to provide passenger standing space on the lower floor behind the upper room sofa and open to above the level thereof, a lower room ceiling above said standing space, and a storage space for the adjacent upper room above said ceiling.

11. In a vehicle, a lower room having a floor and a ceiling, an outer end wall extending from the floor to the ceiling, an inner end wall comprising two horizontally offset vertical portions connected by a horizontal portion providing an alcove, a sofa wholly within said alcove whereby

10 the floor space between the outer edge of said sofa and the outer end wall provides standing room to the height of said ceiling, an upper room adjacent to the lower room having a floor disposed above the level of the lower room floor and having a sofa disposed directly above the lower room sofa, wholly within the plan projection thereof and spaced longitudinally of the vehicle between the lower room ceiling and the upper room floor, and a storage space for the upper room above the ceiling of the lower room.

15 12. In a vehicle, a lower room having a floor and a ceiling, an outer end wall extending from the floor to the ceiling, an inner end wall comprising two horizontally offset vertical portions connected by a horizontal portion providing an alcove, a sofa wholly within said alcove whereby the floor space between the outer edge of said sofa and the outer end wall provides standing room to the height of said ceiling, an upper room adjacent to the lower room having a floor disposed above the level of the lower room floor and having a sofa disposed directly above the lower room sofa, wholly within the plan projection thereof and spaced longitudinally of the vehicle between the lower room ceiling and the upper room floor, and a storage space for the lower room beneath the floor of the upper room and having a floor at substantially the level of the lower room floor.

20 13. In a vehicle having a lower floor, an upper room, a ceiling therefor, an end wall for the upper room comprising two horizontally offset substantially vertical partition portions extending from said ceiling to the lower floor and connected by a substantially horizontal portion, a sofa for the upper room mounted over the horizontal portion of the offset partition, a floor for the upper room extending horizontally from the lower vertical portion of the offset partition, a 25 stairway extending from the lower floor to the floor of the upper room, a lower room having a ceiling extending from the upper vertical portion of the offset partition, an end wall extending from said lower room ceiling to the lower floor, a bed beneath the sofa of the upper room, and a storage space above the ceiling of the lower room.

30 14. In a vehicle, an aisle extending lengthwise of the vehicle, a pair of adjoining rooms adjacent to one of the vehicle sides and disposed side by side with one room partially over the other room, the lower room having its floor at the level of the aisle floor, and the upper room having its floor above the level of the aisle floor, a stairway leading from the aisle floor to the upper room, the wall separating said two rooms comprising lower and upper horizontally offset substantially vertical portions connected by a substantially horizontal portion, one of said vertical portions and the horizontal portion lying within the vertical projection of the lower room, a sofa in the upper room in the vertical projection of said horizontal portion and convertible into a bed, and a sofa in the lower room, the floor of the upper room lying wholly outside the vertical projection of the lower room.

35 15. In a vehicle having a lower floor, an upper room, a ceiling therefor, an end wall for said upper room comprising horizontally offset substantially vertical partition portions extending from said ceiling to the lower floor and connected by a partially inclined and partially horizontal partition portion, the horizontal portion being adjacent to the lower vertical partition portion, a sofa for the upper room mounted over the hori-

zontal partition portion, a floor for the upper room extending from the lower vertical portion of the offset partition, a stairway extending from the lower floor to the floor for the upper room, a lower room having a ceiling extending from the upper vertical portion of the offset partition, an end wall extending from said lower room ceiling to the lower floor, and a convertible sofa bed beneath the sofa of the upper room in the angle formed by the lower vertical portion and the lower floor, the sofa being disposed directly below the inclined partition portion and projecting beyond the vertical projection of the inclined partition portion.

16. In a vehicle having an aisle extending lengthwise thereto, an upper room between the aisle and one vehicle side and having a floor above the level of the aisle floor, a lower room adjoining the upper room and having a floor at a level below the upper room floor, a substantially straight aisle partition separating the rooms from the aisle, a stairway leading from the aisle floor to the floor of the upper room and commencing in the plane of the aisle partition, a door for the upper room at the top of the stairway and when closed lying in the plane of the aisle partition, and means associated with the

- door for closing the space between the upper room floor and the door when said door is closed.
17. In a vehicle having an aisle extending lengthwise thereto, an upper room between the aisle and one vehicle side and having a floor above the level of the aisle floor, a lower room adjoining the upper room and having a floor at a level below the upper room floor, a substantially straight aisle partition separating the rooms from the aisle, a stairway leading from the aisle floor to the floor of the upper room and commencing in the plane of the aisle partition, a door for the upper room at the top of the stairway and when closed lying substantially in the plane of the aisle partition, and means associated with the door for closing the space between the upper room floor and the door when said door is closed, said means comprising a box having a vertical side formed by the lower portion of the door, a second side extending horizontally inwardly from the door closely adjacent to the room floor, and a third side extending diagonally upwardly from the inner edge of the horizontal side of the box.

CERTIFICATE OF CORRECTION.

Patent No. 2,364,094.

December 5, 1944.

PETER PARKE, ET AL.

It is hereby certified that error appears in the printed specification of the above numbered patent requiring correction as follows: Page 2, first column, line 32, after the numeral "41" strike out "of"; and that the said Letters Patent should be read with this correction therein that the same may conform to the record of the case in the Patent Office.

Signed and sealed this 20th day of February, A. D. 1945.

Acting Commissioner of Patents.

zontal partition portion, a floor for the upper room extending from the lower vertical portion of the offset partition, a stairway extending from the lower floor to the floor for the upper room, a lower room having a ceiling extending from the upper vertical portion of the offset partition, an end wall extending from said lower room ceiling to the lower floor, and a convertible sofa bed beneath the sofa of the upper room in the angle formed by the lower vertical portion and the lower floor, the sofa being disposed directly below the inclined partition portion and projecting beyond the vertical projection of the inclined partition portion.

16. In a vehicle having an aisle extending lengthwise thereto, an upper room between the aisle and one vehicle side and having a floor above the level of the aisle floor, a lower room adjoining the upper room and having a floor at a level below the upper room floor, a substantially straight aisle partition separating the rooms from the aisle, a stairway leading from the aisle floor to the floor of the upper room and commencing in the plane of the aisle partition, a door for the upper room at the top of the stairway and when closed lying in the plane of the aisle partition, and means associated with the

- door for closing the space between the upper room floor and the door when said door is closed.
17. In a vehicle having an aisle extending lengthwise thereto, an upper room between the aisle and one vehicle side and having a floor above the level of the aisle floor, a lower room adjoining the upper room and having a floor at a level below the upper room floor, a substantially straight aisle partition separating the rooms from the aisle, a stairway leading from the aisle floor to the floor of the upper room and commencing in the plane of the aisle partition, a door for the upper room at the top of the stairway and when closed lying substantially in the plane of the aisle partition, and means associated with the door for closing the space between the upper room floor and the door when said door is closed, said means comprising a box having a vertical side formed by the lower portion of the door, a second side extending horizontally inwardly from the door closely adjacent to the room floor, and a third side extending diagonally upwardly from the inner edge of the horizontal side of the box.
